UNITED STATES PATENT OFFICE.

AUGUSTINUS EDWARD JONSSON, OF LIDINGO VILLASTAD, SWEDEN.

DRYING APPARATUS.

Application filed April 22, 1925. Serial No. 25,039.

To all whom it may concern:

Be it known that I, AUGUSTINUS EDWARD JONSSON, a subject of the King of Sweden, residing at Lidingo Villastad, Sweden, have 5 invented new and useful Improvements in Drying Apparatus, of which the following is a specification.

This invention relates to such drying apparatus which are provided with stirring means and in which the goods is dried under a great vacuum by means of heating surfaces, which are arranged in the apparatus and also may serve as distributers or spreaders for the drying goods and eventually divide the apparatus in several compartments or chambers. In such known drying apparatus the desired vacuum is obtained by means of a pump or the like, connected to the drying apparatus by a conduit, and 10 the stirring is produced by wings, endless screws or the like, arranged upon a shaft rotated from the outside of the drying apparatus. The experience, however, has proved that it is extremely difficult to effect 15 and maintain an air tight journalling of the said shaft in such drying apparatus, for which reason it has not been possible to maintain in any desired degree the desired vacuum in drying apparatus of that kind.

According to the present invention this 20 difficulty is overcome in a very simple manner by the arrangement of the drying apparatus movably upon external bearings without the use of any shaft passing through 25 it and by connecting the vacuum pump with the drying apparatus by means of one or more flexible conduits which are firmly connected to the said apparatus. By giving 30 the drying apparatus an oscillating movement one or some turns the necessary stirring of the drying goods is effected, while at the same time the drying apparatus remains completely tight, without any stuffing boxes or the like, so that the work of 35 the pump is limited to the removal of the vapors and gases generated during the drying operation.

In the accompanying drawings a constructional form of a drying apparatus, arranged 40 according to the present invention is illustrated in side elevation in Fig. 1, in cross

section in Fig. 2 and in an end view in Fig. 3. The drying apparatus consists of a cylindric container 1 which is oscillating upon rollers 2; this container is not provided with any shaft passing through it, thus rendering stuffing boxes and the like unnecessary. It is oscillated by means of a motor 3, which is automatically reversible and turns the container 1 by pinions 14 gearing with toothed rims 15. 4 and 5 are chambers which are fed with steam, hot water or any other suitable heating fluid through the flexible conduits 6, firmly connected to the container, while the cooled heating fluid escapes 45 through the also flexible conduit 7 firmly connected to the container. The heating chambers 4 and 5 are connected with one another so that an effective distribution of the heating fluid is obtained. 8 are openings 50 for the introduction of the corn to be dried, which corn at the emptying of the container is tipped out in the ducts 12 at the sides of the container.

The vacuum required for an effective and 55 rapid drying is caused by the conduits 10, which are connected to a vacuum pump by an intermediate condenser 9 and also to the container 1 in such a manner that a completely air tight connection between these two 60 members is obtained, whereby the pump also by small dimensions will be able to maintain a very high vacuum in the container. For guiding the flexible conduits 6, 7 and 10 a support 11 of suitable kind may be used and the said conduits may also at that part of them surrounded by the support be reinforced for preventing their wear. The apparatus for generating the vacuum may of course be of any suitable construction for instance an ejector pump.

Having now particularly described the nature of my invention and the manner of its operation, what I claim is:

1. Drying apparatus with stirring means, 65 in which the goods is dried under a great vacuum by means of heating surfaces, situated in the apparatus, characterized thereby, that the apparatus is movably mounted upon bearings and connected with 100 a vacuum pump by flexible conduits for the purpose of permitting an oscillating move-

ment of the apparatus one or more turns for stirring the goods without the necessity of using stuffing-boxes or the like.

2. A constructional form of the drying apparatus as claimed in the preceding claim to be used if the heating means consist of steam or hot water chambers, characterized thereby, that the conduits for carrying the

heating fluid to and from the chambers also are flexible and firmly connected to the 10 drying apparatus in such a manner that they permit the oscillating movement of the drying apparatus.

In testimony whereof I have signed my name to this specification.

AUGUSTINUS EDVARD JONSSON.
